UNITED STATES PATENT OFFICE.

DEL ROY F. FOWLER, OF MELROSE PARK, PENNSYLVANIA.

UPHOLSTERY PADDING.

Application filed January 22, 1925. Serial No. 4,060.

My invention relates to a padding material for upholstery adapted to be used for stuffing long relatively narrow pockets such as are commonly used in automobile upholstery and which padding is commonly introduced into the pockets by means of a tube, and subjected to considerable longitudinal strains during the necessary handling. Padding of this kind is generally formed by folding a long narrow strip of fibrous material, such as cotton batting, upon itself and heretofore the necessary longitudinal strength has been imparted to the material by folding the sheet of fibrous material over a strip of paper or other strengthening material which becomes a part of the padding. This paper reinforced padding has gone into extensive use in spite of the fact that the paper element of the padding has objectionable features.

The object of my invention is to provide a padding of the kind described in which the paper reinforce or a fabric reinforce used in place of the paper, can be entirely omitted and the necessary longitudinal strength imparted to the padding by other and less objectionable means and this I have discovered can be effected and the necessary longitudinal strength imparted to the padding by forming a line of thread stitches extending through the folded strip longitudinally, the thread stitches serving the double purpose of securing the folded layers of the strip together and imparting to the padding as a whole the necessary longitudinal strength to resist the strains to which it is subjected in use, while at the same time, the thread stitches are easily broken at the points where the padding is torn off after an appropriate length has been used in filling a pocket.

Another feature of my invention consists in providing as a means for holding the overlapping folds of the strip in permanent contact with the underlying layer a line of glue which I have found very efficient for this purpose and the use of which in a padding strip made with a paper reinforce forms the subject matter of my pending application for Letters Patent, Serial No. 743,515, filed October 14, 1924.

The nature of my invention will be best understood as described in connection with the drawing in which—

Figure 1 is a plan view of a strip of padding constructed in accordance with my invention, and

Figure 2 is a cross section through the padding strip.

A indicates the padding made up of a strip of fibrous material, generally cotton batting, folded on itself in layers indicated at B, B', and B², B³ indicating the edge of the upper layer which lies against the underlying layer B. C indicates a line of thread stitches sewed through the layers of fibrous material and extending longitudinally throughout the padding strip. I have shown two lines of stitching C but I have found in practice that for most purposes one line of stitches is quite sufficient to impart the necessary longitudinal strength to the strip of padding. D indicates a line of glue securing the overlapping edge B³ to the underlying layer B.

In practice I enfold the strip of fibrous material on itself, as indicated in Fig. 2, securing the overlapping edge to the underlying layer by the line of glue indicated at D and then by means of a sewing machine I form the line or lines of stitches C running longitudinally, binding the layers of fibrous material together and imparting to them the necessary longitudinal strength.

Having now described my invention, what I claim as new and desire to secure by Letters Patent, is:

1. Upholstery padding adapted for use in stuffing narrow pockets comprising in combination a long sheet of fibrous material folded on itself to form a long and narrow pad and one or more lines of thread stitches extending through the folded sheet and running longitudinally thereof said stitch lines serving as the sole means whereby the resistance of the pad to longitudinal strains tending to break it is increased and by the use of which a paper reinforce or cover is made unnecessary.

2. A pad having the features of claim 1 and further characterized by having its outer overlapping edge secured to the underlying layer by a line of glue.

DEL ROY F. FOWLER.
